UNITED STATES PATENT OFFICE.

HENRY J. DENGLER, OF ROCHESTER, NEW YORK, ASSIGNOR OF ONE-HALF TO CONNELL
& DENGLER MACHINE CO., OF ROCHESTER, NEW YORK, A CORPORATION.

PRINTING-MACHINE.

1,200,597.

Specification of Letters Patent.

Patented Oct. 10, 1916.

Application filed August 18, 1914. Serial No. 857,317.

To all whom it may concern:

Be it known that I, HENRY J. DENGLER, of Rochester, in the county of Monroe and State of New York, have invented a new 5 and useful Improvement in Printing-Machines, which improvement is fully set forth in the following specification and shown in the accompanying drawings.

The present invention relates to printing 10 machines and more particularly to the type employed for printing upon corrugated board, paper board, card board and other similar material, an object of the invention being to provide a construction in which the 15 operative may stand upright at the intake end of the machine and feed the sheets by holding one side thereof, thus making the work of the operative easier and dispensing with the large feed table on which the work 20 is usually supported at the intake end of the machine.

Another object of the invention is to provide a machine which will be adapted to feed sheets either in a flat condition or which will 25 subject the sheets to a slight bending action so as to cause the forward edge of the sheet to enter the gripping means in a flat condition when the corners thereof are curled or bent.

30 Other objects of the invention are to improve the feeding mechanism which carries the work past the printing mechanism and to improve the discharge end of the machine so that the sheets when released by the 35 gripping members will be discharged from the bed of the machine.

To these and other ends the invention consists in certain parts and combinations of parts all of which will be hereinafter 40 described, the novel features being pointed out in the appended claims.

In the drawings: Figure 1 is a side view 45 of a printing machine embodying the present invention; Fig. 2 is a plan view of the intake end of the machine; Fig. 3 is an enlarged view of the intake end of the machine in side elevation with parts broken away; Fig. 4 is an enlarged vertical section through the intake end of the machine showing the 50 machine adjusted for feeding sheets; which it is desired not to bend to any great degree;

Fig. 5 is a view similar to Fig. 4 showing the machine adjusted for feeding cardboard or other material which it is desired to flatten out at the forward edge; Fig. 6 is a detailed 55 sectional view of the discharge end of the machine showing one sheet fed from the machine by a gripping member; Figs. 7 and 8 are detailed sectional views through one of the gripping members; Fig. 9 is a detailed 60 sectional view through the bed of the machine showing a portion of one of the gripping members in raised position; Fig. 10 is a plan view of a portion of one of the gripping members removed from the machine; 65 Figs. 11 and 12 show one of the clamps of one of the gripping members in two positions. Fig. 13 is a detail view showing the intake end of the machine adjusted for printing on material which should not be bent, 70 such as corrugated board, and Fig. 14 is a plan view of a portion of the intake end of the machine adjusted as shown in Fig. 13. Fig. 15 is a detail view of a construction 75 showing the discharging roller rotating at a greater speed than the feed belt moves to carry the work away from the shoulders on the gripping bars or members.

Referring more particularly to the drawings, 1 indicates the side frames of the machine connected at their ends by end pieces 2 and supporting a bed or plate 3 over which the work is carried by a suitable feeding mechanism to be described in order that the work may be operated on by a printing 80 mechanism 4 of any suitable construction and preferably embodying two printing rollers 4 driven in any suitable manner as by the gearing shown in Fig. 1 from a drive shaft 5, the rollers operating in a well known 85 manner on the work as the latter is carried over the bed 3.

For feeding the work over the bed, a feeding mechanism is employed comprising preferably two endless chains 6 each passing 90 about pulleys at the intake end of the machine and about pulleys 8 at the delivery or discharge end of the machine. These endless chains operate in grooves 9 formed in the bed 3 near the opposite side frames of 95 the machine and are connected at intervals by gripping member bars 10. The gripping

members preferably comprise bars 10, L-shaped in cross section and having their under faces provided with transverse parallel ribs 11 for operating within grooves 12 formed in the upper surface of the bed 3. The upper faces of the horizontal portions of these bars 10 are beveled near their free edges at 13 so as to facilitate the introduction of the sheets within the pocket 14 5 formed above the horizontal portion of the bar 10 by what are termed hopper extensions 15, the free edges of which are also beveled at 16 to facilitate the introduction of the sheet of material into the pocket 14. These 10 hopper extensions 15 of which there are two on each bar 10, may be secured to the bar 10 by bolts 17 which pass through spacing lugs 17^a that space the extensions 15 from the upright portion of the bar. Guided between the vertical portion of the bar 10 and the hopper extensions 15 are two slide bars 18 which have laterally-extending projections 19 operating within slots 20 formed in clamping dogs 21.

25 The clamping dogs 21 are preferably pivoted below the slide bars 18 on pivot pins 22 and have clamping faces 23 which are adapted to coöperate with the horizontal portion of the L-shaped bar 10. Springs 24 are coiled about the pivot pins 22 and each has two arms, one bearing against a lug 25 on the dog and the other against a stud 26 on the bar 10, these springs normally tending to move the dogs or clamps 22 so that 30 their engaging faces 23 will clamp the material against the horizontal portion of the bar 10. In this instance, two dogs or clamps are controlled by each operating bar 18 and this operating bar is in turn operated to 35 place the springs under tension in order to lift the engaging faces 23 of the dogs away from the horizontal portion of the clamping bar 10. This may be effected by fixed cams 27 arranged at opposite ends of the machine 40 in pairs, the members of which are located on opposite sides of said machine to coöperate with the rollers 28 on the ends of the bars 18. With this arrangement the dogs or clamps are elevated at the intake of the 45 machine to receive the sheets and at the discharge end of the machine to free the sheets. It is apparent also that after a sheet is freed by the clamps, it rests upon the bed of the machine until the next gripping bar coöperates with its rear edge when it will be shifted by such bar off the table, this being 50 due to the fact that the bed is located substantially in a plane with the under side of the bar 10 and the bar has projections which 55 operate in grooves in the bed to prevent the sheet passing beneath the bar.

Combined with the endless feeding means is an intake feeding mechanism, the construction and arrangement of which is such 60 that it permits the operative to stand up- 65

right close to the intake of the machine in order to handle the stock and properly position the same in the clamping members. This is obtained by having the discharge point of said intake feeding mechanism located at a distance from the intake end of the bed less than the distance between the gripping or clamping members on the endless feeding means. In one instance, a feed table 29 is supported in an inclined position 70 by two standards 30 which, by bolts 31, are removably and adjustably secured to the side frames 1, the bolts operating in a slot 32 in the standards 30 to permit the table 29 to be adjusted in the direction of the feed 75 of the machine toward and from the printing mechanism for a purpose which will be hereinafter set forth. Upon the feed table 29, a gage is arranged which preferably is in the form of an upstanding board or flange 80 85 33 to determine the position of one edge of the work on the table. This gage may be adjustable transversely of the table and to this end carries the bar 34 operating in the groove 35 in the upper surface of the table, 90 the bar being of wedge-shape and the groove being correspondingly formed so that a binding action between the bar and the groove is obtained when the thumb nut 36 is operated to clamp the parts together. 95

At the forward edge of the table, a roller 37 is provided operating in laterally opening bearings 38, and for coöperation with this roller, a number of rollers 39 are adjustable axially on a shaft 40 and tend to 100 engage the work and feed the latter quickly to the gripping members while the latter are open at the intake end of the machine. The shaft 40 may be mounted on a swing carrier 42 which turns about an axis 43 105 above the feeding belt and in spaced relation to the latter in boxes or standards 44 projecting upwardly from the side frames 1 of the machine. This carrier 42 may be provided with a laterally-extending arm 45 at 110 one side of the machine for coöperation with a cam member 46, the arm having a laterally projecting roller 47 which is engaged by the cam member. The cam member may be rotated in such a manner that it engages 115 the roller 47 and moves the rollers 39 toward rollers 37 as each of the clamping members is opened at the intake end of the machine, coöperative action between the rollers 39 and the rollers 37 being maintained by the 120 cam until the work is fed by such rollers into the jaw of the clamping member. The cam may be rotated by a large gear 48 which, through a gear 49, connects with the gearing of the printing mechanism so as to 125 be operated with said printing mechanism. In order to drive the shaft 40 on which the rollers 39 are mounted, said shaft is provided with a sprocket wheel 50 which, by a sprocket chain 51, is connected to the 130

sprocket wheel 52 on the shaft of which is arranged a gear wheel 53 which meshes with the gear 49 so that the rollers 39 are also rotated and driven from the printing mechanism.

To hold the arm 45 of the swinging or oscillating frame 42 in connection with the cam 46, the arm 45 is provided with an eccentric projection 100 which is engaged by a spring 101 anchored at 102 on the side frame 1. Arm 45 is also adjustable and clamped at 103 to the shaft 43 in order that the rollers 39 may be made to move nearer to or farther away from the roller 37 to accommodate sheets of different thicknesses.

As the roller 37 is mounted on the adjustable table 29, it is apparent that this roller may be moved toward and from the axis of rotation 43 of the swinging carrier 42. In this way, it is possible to cause the cooperation between the rollers 39 and 37 to act on the material in such a manner as to bend the material so that the forward edge of the latter is caused to bear with pressure against the feed table. This causes any curled corners on the sheet material to be flattened against the bed in order that the forward edge may be properly introduced into the jaws of the clamping member. This adjustment which is illustrated in Fig. 5 is especially designed for paper board which has a tendency to curl at its corners. With other material, the bending of the same to any great extent is undesirable and the roller 37 is therefore moved nearer to the axis 43 as shown in Figs. 3 and 4.

With some material, such, for instance, as corrugated board, any bending thereof must be avoided, and to print on the same, the machine is adjusted as shown in Figs. 13 and 14 in which the intake feeding mechanism shown in the other figures is entirely removed except for the gear 48 and the cam 46 and, in place thereof, an intake feeding mechanism of similar construction and operation is employed except that instead of operating in the plane above the plane of the endless feeding means, it operates in a plane with said endless feeding means so that the work is fed by the intake feeding mechanism in a straight line toward the clamping members. In this construction, an oscillating frame 42^a turns about an axis 43^a supported on standards or brackets 44 above the endless feeding belt, the brackets being arranged closer to the intake end of the machine than in Figs. 3 and 4. On the oscillating frame, an arm 45^a is formed of greater length than the arm 45 to coöperate with the cam 46 and this arm is adjustably secured at 103 to the shaft 43^a and is held against the cam 46 by a spring 101 engaging the projection 100. On the oscillating frame 42 a shaft 40^a is arranged which carries the roller 39 and is driven by a sprocket chain

51^a in the same manner as shown in Fig. 1. The rollers 39 coöperate with the roller 37^a which is journaled on the side frames 1 in close proximity to the end wall 2. This intake feeding mechanism also operates periodically to carry the work into the clamping members but, as before stated, differs from the arrangement shown in Figs. 3 and 4 in feeding the work in the plane of the effective portion of the endless belt instead of at an angle to such a plane.

When the machine is adjusted as shown in Figs. 13 and 14, it is desirable to employ a table for guiding and supporting the work in rear of the intake feeding rollers. In this instance, this table is not so wide as the machine so that an operative may still stand at the intake end of the machine in an upright position while feeding the work. This table indicated at 54 is vertically adjustable on the machine and, at the same time, is removable. In this instance, it is supported at one end by a rod 55 on which it is longitudinally shiftable. This rod is supported in blocks 56 which, by bolts 57, are held within vertical grooves 58 formed in the wall 2. The outer end of the table may be supported by a leg 59 which is adjustable at 60 to correspond to the adjustment of the blocks 56. By having the table adjustable laterally of the feeding line of the machine, it is possible to position the same in line with the type on the printing cylinders for it will be understood that, in many instances, the sheets of material are not so wide as the machine and consequently the type is arranged at different positions on the printing cylinders. While the table will, preferably, be located in a plane with the effective portion of the endless feeding mechanism, it can be raised or lowered on the frame and serve as a support for a stack of sheets either with the construction shown in Figs. 13 and 14 or with the construction shown in Figs. 3 and 4, the sheets in the latter case being lifted to the table 29 by the operative, as shown in Fig. 3.

To the end of assisting the gripping members in the discharge of the work from the discharge end of the machine, there is arranged at such discharge end beyond the wall 2, a roller 61, the peripheral speed of which, in this instance, is substantially the same as the speed of the endless feeding belt but, in some cases, must be faster. This roller may be driven from the shaft 62 which supports the sprocket or by means of a sprocket chain 63 which engages a sprocket 64 on the shaft 62 and a sprocket 65 connected with the pulley 61. After a sheet has been fed about one half way over this roller 61, the roller has a dominating driving action on the sheet and carries the latter slightly in advance of the shoulder on the gripping member and in this way permits

the gripping member to turn downwardly without injury to the rear edge of the sheet.

When the machine is adjusted as shown in Figs. 3 and 4, the operative stands at the intake end of the machine in an upright position, grasping the sheet at one side from a suitable supply and presenting the forward edge between the rollers 37 and 39 of the intake feeding mechanism with the opposite edge against the gage 33. The rollers 39 which are normally separated from the roller 37 move toward the latter and grip the work, after which the latter is carried forward at a greater speed than the endless chains 6 until the forward edge of the sheet enters a gripping member which is open ready to receive said edge. About this time, the clamping member grips the sheet and the rollers 39 move above from the roller 37 so that the sheet is carried forward by the clamping member past the printing mechanism. After the latter has been passed, the gripping member releases the sheet which rests upon the bed 3 until the forward edge of the next gripping members engages with the rear edge of the sheet and moves the latter onto the roller 61. The latter causes the discharge of the sheet from the machine as shown in Fig. 6.

With some sheets which are curled at their forward corners, making the entry of the sheets into the clamping member otherwise difficult, the intake feeding mechanism is adjusted as shown in Fig. 5 so that the rollers 39 tend to bend the sheet downwardly with pressure against the bed 3, thus flattening the forward edge against the bed and causing a proper entry of the edge into the gripping member.

Some material, such as corrugated board, cannot be bent and when this is to be printed, the intake mechanism shown in Figs. 4 and 5 is removed from the machine and that shown in Figs. 13 and 14 substituted. With this latter arrangement, the sheets are fed to the rollers 37a and 39 as in the other arrangement except that they enter the machine in a plane with the effective portion of the feeding belt.

A machine constructed in accordance with this invention makes it possible to print on most any kind of flat sheets, especially those used for packing purposes as card or paper board and corrugated paper. The operative can feed the machine while standing upright or sitting at the intake end of the machine, it being unnecessary for him to bend over one side of the machine to feed the work to the machine. The intake feeding mechanism is so adjustable that it may be made to bend the work so as to flatten out any curled edges of the sheets before the latter are presented to the clamping members. Means is also provided for feeding the

work to the machine in a plane with the line of feed through the machine, while, at the same time, not requiring the operative to bend over the machine while holding the work, so that all bending of the stock is eliminated. A novel method of discharging the work is also provided, the work being dropped by one gripping member on the bed and removed from said bed by a succeeding gripping member. A further feature is the table at the intake end of the machine permitting the operative to support the work in desired position before presenting the same to the intake feeding mechanism.

What I claim as my invention and desire to secure by Letters Patent is:—

1. A printing machine comprising a printing mechanism, an endless feeding means for feeding the work past the printing mechanism, said feeding means having a plurality of gripping members for cooperating with the forward edge of the work, and an intake feeding mechanism arranged to feed the work to the gripping members at a distance from the intake end of the machine less than the distance between the gripping members on the endless feeding means so that the work may project beyond the end of the machine to be held by an operative as it is engaged by a gripping member, said mechanism moving the work at a greater speed than the gripping members travel so that the work may be engaged by the gripping members while the latter are moving.

2. A printing machine comprising a printing mechanism, an endless feeding means for feeding the work past the printing mechanism, said feeding means having a plurality of gripping members, an intake feeding mechanism embodying two rollers, to feed the work to the gripping members, the rollers being located at a distance from the intake end of the machine less than the distance between the gripping members, so that the work may project beyond the intake end of the machine while engaged by a gripping member, mechanism for moving one roller toward the other at intervals to cause the intake feeding, and means for opening the gripping members to receive the work from the intake feed mechanism.

3. A printing machine comprising a printing mechanism, an endless feeding means for feeding the work past the feeding mechanism, said feeding means having a plurality of spaced gripping members, two rollers to feed the work to the endless feeding mechanism, said rollers being located a distance from the intake end of the machine less than the distance between the gripping members, mechanism for causing said feed rollers to intermittently feed the sheets to said gripping members at a greater speed.

than the endless feeding means travels, and a table leading to one of said rollers, said table being arranged above the endless feeding means and at an angle to the plane of feed through the machine.

4. A printing machine comprising a printing mechanism, an endless feeding means for feeding work past the printing mechanism, said feeding means having a plurality of spaced gripping members, two rollers to feed the work to the endless feeding mechanism at an angle to the line of feed of said work, one of said rollers being mounted to move toward and from the other to produce or stop the feeding action and the other roller being adjustable transversely of the line of movement of the first mentioned roller.

5. A printing machine comprising a printing mechanism, an endless feeding means for feeding work past the printing mechanism, said feeding means having a plurality of spaced gripping members, a table arranged above and at an angle to the line of feed of the machine, and adjustable in the direction of the line of feed, a roller carried by said table to be adjusted therewith, and a roller movable toward and from the first named roller and mounted independently of said roller so that the latter may be adjusted relatively thereto with the table.

6. A printing machine comprising a printing mechanism, an endless feeding means for feeding the work past the printing mechanism, said feeding means having a plurality of spaced gripping members, two feed rollers arranged above the line of feed to feed material to the gripping members, an oscillatory frame on which one of said rollers is mounted, an arm adjustably mounted on said frame, a cam for moving said arm to cause the roller to move toward the stationary roller, and a spring for moving said oscillatory frame to carry the roller thereon away from the stationary roller.

7. A printing machine comprising a printing mechanism, an endless feeding means for feeding work past the printing mechanism, said feeding means having a plurality of spaced gripping members, a table arranged above the plane of feed of the machine and at an angle thereto, a roller carried by the table, means for effecting the adjustment of the table and the roller in the direction line of feed through the machine, an oscillating frame, a roller carried by said frame to cooperate with the roller on the table, and means for oscillating the frame periodically to cause the work to be fed to the gripping members.

8. A printing machine comprising a printing mechanism, a bed projecting at the discharge end of the machine, an endless

feeding means for carrying the work past the printing mechanism and over said bed, said feeding means having a plurality of gripping members for gripping the forward edges of the sheets, each member having a shoulder to engage the rear edge of a sheet deposited on the bed in advance of it, means for successively operating said gripping members to release each sheet on the bed of the machine after the printing mechanism has been passed so that the shoulder on the following gripping member will push the sheet off the bed and means arranged beyond the path of said gripping members for advancing the sheet away from the shoulders of the gripping members so that the latter may turn downwardly at the end of the machine without injury to the sheets.

9. A printing machine comprising a printing mechanism, a bed projecting from the discharge side of the printing mechanism, a pair of endless sprocket chains, a plurality of gripping members, each connecting said chains and carried by the latter past the printing mechanism and over said bed, said gripping members being adapted to grip the forward edges of the sheets and each having a shoulder to engage the rear edge of a sheet deposited on the bed in advance of it, means for successively operating said gripping members to release each sheet on the bed after the printing mechanism has been passed so that the shoulder on the following gripping member will push the sheet off the bed, and means arranged beyond the path of the gripping members for advancing said sheets away from said shoulder on the gripping members so that the latter may turn downwardly with the endless chains, so that the gripping members may turn downwardly at the end of the machine without injury to the sheets.

10. A printing machine comprising a printing mechanism, a bed projecting from the discharge side of the printing mechanism, a pair of endless sprocket chains, a plurality of gripping members, each connecting said chains and carried by the latter past the printing mechanism and over said bed, said gripping members being adapted to grip the forward edges of the sheets and each having a shoulder to engage the rear edge of a sheet deposited on the bed in advance of it, means for successively operating said gripping members to release each sheet on the bed after the printing mechanism has been passed, so that the shoulder on the following gripping member will push the sheet off the bed, and means for advancing said sheets away from said shoulder on the gripping members so that the latter may turn downwardly with the endless chains, said means embodying a suitably driven roller arranged adjacent the end of the machine beyond the path of the gripping

members, so that the latter may turn downwardly at the end of the machine without injury to the sheets.

11. A printing machine comprising a printing mechanism, a bed, a pair of endless chains, gripping members connecting said chains and moved by the latter over the bed, means for operating said gripping members to release the work on the bed to permit the following gripping member to push the work off the bed, and a suitably driven roller operating at the end of the bed to carry the work off the bed in conjunction with said gripping members.
12. A printing machine comprising a printing mechanism, and an endless feeding means for moving the work past the printing mechanism, said feeding means having gripping members, each embodying two bars having flaring portions for receiving a sheet between them, and a dog movable relatively to the flaring portions for gripping the material passed between said portions.
13. A printing machine comprising a printing mechanism, and an endless feeding means for moving the work past the printing mechanism, said feeding means having gripping members, each embodying an L-shaped bar having a portion thereof upright, a hopper extension rigidly secured to the upright portion, and a dog mounted to grip material introduced between the hopper extension and the horizontal portion of the bar.
14. A printing machine comprising a printing mechanism, endless feeding means for moving the work past the printing mechanism, said feeding means being gripping members, each embodying an L-shaped bar with a portion upright, a hopper extension secured to the bar in spaced relation to both portions of the latter, spring dogs pivotally mounted on the upright portion, and a slide bar for operating the dogs.
15. A printing machine comprising a printing mechanism, a bed having parallel grooves in the upper surface thereof, an endless feeding means for moving the sheet material over the bed past the printing mechanism, said means embodying spaced gripping members for gripping the forward edges of the sheets, said gripping members having ribs operating in the grooves, and intake feeding mechanism arranged to deflect the sheets with pressure at its forward edge against the bed to flatten such edge and then to feed the same to a gripping member in the flattened condition.
16. A printing machine comprising a printing mechanism, a bed, an endless feeding means for carrying the work over the bed past the printing mechanism, said feeding means having gripping members, means for opening the gripping members in proximity to the intake end of the bed, and an

intake feeding mechanism adapted to feed the work to said open clamping members in a plane with the line of feed over the bed.

17. A printing machine comprising a printing mechanism, a bed, an endless feeding means for carrying the work over the bed, said feeding means having clamping members, means for opening the gripping members in proximity to the intake end of the bed, a roller arranged at the intake end of the bed and having its uppermost portion operating in the plane of operation of the clamping members over the bed, and a second roller movable periodically toward and from the first-named roller to feed the work to the gripping members while the latter are open.

18. A printing machine comprising a printing mechanism, an endless feeding means for carrying the work past the printing mechanism, said feeding means embodying a plurality of gripping members for gripping the forward edges of the sheets, each member having a shoulder to engage the rear edge of a sheet released by a gripping member in front of it, means for successively operating the gripping members to release the sheet after the printing mechanism has been passed so that the shoulder on the following gripping member will push the sheet after it is released, and a roller onto which the sheets are pushed, said roller operating at a greater speed than the endless feeding means so that the sheets are advanced ahead of the shoulders of the gripping members after being engaged by such roller.

19. A printing machine comprising a printing mechanism, feeding means for carrying the work to and through the printing mechanism and a feed table at the intake end of the machine of less width than the feeding means so that the workman may stand close to the end of the machine at the side of the table.

20. A printing machine comprising a printing mechanism, feeding means for carrying the work to and through the printing mechanism and a feed table at the intake end of the machine of less width than the feeding means so that the workman may stand close to the end of the machine at the side of the table, said table being adjustable transversely of the line of feed of the feeding means.

21. A printing machine comprising a printing mechanism, feeding means for carrying the work to and through the printing mechanism and a feed table at the intake end of the machine of less width than the feeding means so that the workman may stand close to the end of the machine at the side of the table, said table being adjustable vertically to move the plane of the upper surface thereof.

22. A printing machine comprising a printing mechanism, feeding means for carrying the work to and through the printing mechanism, brackets vertically adjustable on the frame of the machine, a rod carried by said brackets and extending transversely of the line of feed, a table having one side thereof supported on said rod and adjust- able in the direction of the length of the rod and an adjustable support for the opposite side of the table.

HENRY J. DENGLER.

Witnesses:

HAROLD H. SIMMS,
FRANCES JACOBORITZ.

It is hereby certified that in Letters Patent No. 1,200,597, granted October 10, 1916, upon the application of Henry J. Dengler, of Rochester, New York, for an improvement in "Printing-Machines," an error appears in the printed specification requiring correction as follows: Page 6, line 22, claim 12, for the words "flaring portions" read *bars*; and that the said Letters Patent should be read with this correction therein that the same may conform to the record of the case in the Patent Office.

Signed and sealed this 21st day of November, A. D., 1916.

[SEAL.]

F. W. H. CLAY,
Acting Commissioner of Patents.

CL. 101-36.
